TERMINAL BLOCK FOR MOTORS AND
THE LIKE

John A. Draxler, Cleveland Heights, Ohio, assignor to The Elwell-Parker Electric Company, Cleveland, Ohio, a corporation of Ohio

Application July 23, 1943, Serial No. 495,940

4 Claims. (Cl. 171—252)

1

This invention relates, as indicated, to a terminal block, but has reference more particularly to a terminal block which is especially adapted for use in connection with the motors employed on industrial trucks for driving, lifting and other operations usually associated with such trucks.

Heretofore, it has been customary to make the motor leads of motors designed for use on industrial trucks extremely long, so as to enable the motors to be used in a wide range of industrial truck models without resorting to the undesirable practice of splicing wires. At the present time, however, and due to the shortage of critical materials, such as copper wire, the use of such long leads is highly undesirable, and, in some instances, virtually prohibitive.

The present invention, accordingly, has as its primary object the conservation of such materials by the provision of a terminal block, made of non-critical materials, and the use of which renders unnecessary the use of motor wires of extreme length.

Another object of the invention is to provide a terminal block which can be entered in either of two directions for the connection therewith of the motor wires.

A further object of the invention is to provide a terminal block and mounting therefor on a motor, the use of which greatly facilitate disassembly of certain of the motor parts.

A still further object of the invention is to provide a terminal block of rugged simple construction, and made of a minimum number of parts which can be readily assembled and disassembled.

A still further object of the invention is to provide a cable terminal of novel construction.

To the accomplishment of the foregoing and related ends, said invention, then, consists of the means hereinafter fully described and particularly pointed out in the claims; the annexed drawings and the following description setting forth in detail certain structure embodying the invention, such disclosed means constituting, however, but one of various structural forms in which the principle of the invention may be used.

In said annexed drawings:

Fig. 1 is a perspective view of a terminal block made in accordance with the invention, with portions broken away to more clearly show the construction;

Fig. 2 is a view, partly in elevation, and partly in section, showing the manner in which the block is mounted upon a motor;

Fig. 3 is a fragmentary cross-sectional view,

2

showing a terminal connection to the block which is made from one side of the block;

Fig. 4 is a view similar to Fig. 3 but showing the terminal connection made from the other side of the block;

Fig. 5 is a plan view of the assembled lower portions of the terminal block;

Fig. 6 is a side elevation of the portions shown in Fig. 5;

10 Fig. 7 is a plan view of the upper portion of the terminal block;

Fig. 8 is a side elevation of the portion shown in Fig. 7, and

Fig. 9 is an end elevation of the terminal block.

15 Referring more particularly to the drawings, reference numeral 1 designates a motor housing having a vertical extension 2 providing a rectangular opening 3 at its upper end, the ends of the opening being bounded by flanges 4' which are integral with the extension 2.

20 Mounted on the vertical extension 2 of the motor housing is a terminal block which consists of three parts, an upper portion 4, and a pair of lower portions 5. The lower portions 5 are of identical construction, being provided with tenon-like projections 6 at the bottom, which extend into the opening 3 and which conjointly substantially fill the upper portion of said opening.

30 Each of the lower portions 5 also has a series of longitudinally spaced semi-circular recesses 7 in one of its vertical faces, the recessed faces of the portions 5 being in contact with each other, and the recesses in one portion being opposite 35 those in the other portion, so as to conjointly form circular vertical holes 8 (Fig. 5).

Each of the portions 5, moreover, has a series of longitudinally-spaced semi-circular recesses 9 in its upper surface which extend transversely 40 of the recesses 7 and in communication with the latter, the recesses 9 in one of the portions 5 being in registration with the recesses 9 in the other portion 5.

45 The upper portion 4 of the terminal block rests directly upon the portions 5 thereof, and is provided in its lower surface with a series of longitudinally-spaced transversely extending semi-circular recesses 10, which are disposed opposite the recesses 9 of the portions 5, and conjointly form with the latter, holes 11, the axes of which are normal to the axes of the holes 8.

50 The terminal block is removably secured to the extension 2 of the motor housing by means of screws 12, which extend through the ends of the

block and into the flanges 4', being in threaded engagement with the latter.

The terminal block, as described above, is formed of suitable material of an electrically-insulative character, a number of which is readily available.

The motor is provided with a number of wires or cables 13 which extend into the extension 2 of the motor housing, and are provided with metallic T-shaped terminals, generally designated by the numerals 14. Each of these terminals has a socketed stem portion 15 which is soldered or otherwise secured to the wire 13, and a tubular head portion 16 having a bore 17 extending therethrough, the walls of which are tapered inwardly from the ends of the head to the middle thereof.

Each of the terminals 14 has the stem thereof disposed in one of the holes 8 of the terminal block, and the head 16 thereof disposed in one of the holes 11 of the block, the head 16 being of such a length as to terminate somewhat short of the ends of the holes 11.

The heads 16 of the terminals are adapted for the reception in either end thereof of the taper terminals 18 of wires or cables 19, which lead to the motor, and which terminals are maintained in wedging engagement with the tapered walls of the bores 17 by means of screws 20, the heads of which are in abutment with washers 21, which are interposed between such heads and one end of the heads 16 of the terminals.

By using a terminal block of the aforesaid character, it becomes unnecessary to provide wires of extreme length, which are required to satisfy the requirements of installation of the motor in a wide range of industrial truck models, where splicing of wires is not desired, and moreover, it renders unnecessary the undesirable practice of splicing of wires during such installation. Moreover, the wires from the truck wiring can enter the terminal block in either of two directions, which is a highly advantageous feature, and the wedging engagement of the tapered terminals 18 with the tapered walls of the bores 17 insures a current path of unusually low resistance and precludes the possibility of loose connections, which occurs in cases where wires are led into an untapered cylindrical hole and clamped in position by pinching the wire with one or more machine screws, as in ordinary common practice.

The construction of the block, moreover, is such as to greatly facilitate the disassembly of certain of the motor parts, such as the commutator pedestal.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

1. In combination with a motor housing, a terminal block mounted on said housing, said block comprising a pair of portions having contacting faces, and having recesses in said faces conjointly forming holes, and having recesses in other faces thereof which extend transversely to said holes, and another portion contacting both 70

of said first-named portions and having recesses therein which form holes with the recesses in said other faces, said pair of portions having tenon-like projections which extend into the motor housing to thereby prevent longitudinal or lateral displacement of the block relatively to said housing, and means removably securing the block to said housing.

2. In combination with a motor housing, a terminal block comprising a pair of members having abutting faces, said faces having recesses in registration with one another for forming an opening in the block, said members having recesses in other faces thereof, which recesses extend transversely relative to said opening, a third member adapted to overlie said other faces, said third member having a recess in registration with the recesses in said other faces, said housing having an opening therein, said pair of members having portions which extend into said opening whereby the walls of the opening engage said pair of members for retaining said pair of members substantially in abutting relation; and means for securing said third member to said housing.

3. A terminal structure comprising, a conductor having two cable receiving portions, one of said portions extending transversely of the other of said portions; an insulation housing for said conductor comprising a pair of blocks adapted to be secured in abutting relation, said blocks having recesses therein adapted to lie in registration with one another for forming an opening for receiving one of said conductor portions, the other of said conductor portions being adapted to extend beyond said blocks; a third block adapted to overlie said pair of blocks and having a recess therein for receiving said other portion of said conductor, the walls of said recesses being engageable with said conductor for positioning said conductor; and means for securing said pair of blocks in abutting relation and for securing the third block in overlying relation to said pair of blocks.

4. A terminal structure comprising a conductor having two cable receiving portions, one of said portions extending transversely of the other of said portions; an insulation housing for said conductor comprising a pair of blocks, each of said blocks having a recess in one face thereof and a second recess in another face thereof, said second recess extending transversely relative to first recess, said one faces of said pair of blocks being in abutting relation with the recesses therein in registration with one another for forming an opening for receiving one of said portions of said conductor, the other portion of said conductor extending in said second recesses and a third block adapted to overlie said conductor and said other faces of said pair of blocks, said third block having a recess in registration with said second recesses for forming an opening for said other portion of said conductor whereby the walls of said recesses are engageable with the conductor for positioning the latter; and means for maintaining said pair of blocks in abutting relation and for maintaining said third block in position over said pair of blocks and conductor.

JOHN A. DRAXLER.
